STOKER

William T. Hanna, Cincinnati, Ohio

Application January 12, 1940, Serial No. 313,599

28 Claims. (Cl. 110—105.5)

This invention relates to stokers particularly adapted for firing locomotives. Stokers of this type have a conduit conveying system extending from beneath the locomotive tender up to the firebox of the locomotive. At the discharge end of this conduit system distributing apparatus receives coal from the conveyor system and distributes it over the firebox. The distributing operation is important for the efficiency of the combustion depends to a large extent on accurate coal distribution and on the manner in which the distributing is accomplished. One of the objects of the present invention is to provide for improved coal distribution, and for an improved conveying system for delivering the coal to the distributing apparatus.

Another requirement which a satisfactory stoker must meet is that of taking up a minimum amount of room in the locomotive cab and of fitting in the limited space beneath the front end of the tender. This is particularly true where, as in the present invention, the stoker fires through the hand-firing opening in the backhead of the locomotive boiler and wherein the conduit system extends up through the cab deck. Further, the delivery heads of stokers firing through the hand-firing opening must be constructed to permit free access of repairmen to the interior of the firebox through the hand-firing opening. It is another object of the present invention to provide an improved conveying system meeting the above and other requirements.

In the drawings,

Figure 1 is a vertical longitudinal section of a stoker embodying the invention;

Figure 2 is a detailed section taken on line 2—2 of Figure 1 and showing a mouthpiece of the stoker adjusted to the left of the vertical medial plane of the stoker;

Figure 3 is a perspective view looking from the inside of the firebox out through the firing opening into the delivery end of the conduit system of the stoker of Figure 1;

Figures 4, 5 and 6 are detailed sections of the delivery mouthpiece of the stoker of Figure 1 and taken respectively on lines 4—4, 5—5 and 6—6 of Figure 1;

Figure 7 is a vertical section taken on line 7—7 of Figure 1 and showing the manner in which the distributing apparatus is mounted within the confines of the firing opening;

Figure 7a is a detailed perspective showing the location of parts on the side of the frame supporting the mouthpiece;

Figure 8 shows the delivery end of the stoker of Figure 1 in side elevation and shows a modified connection between a hopper beneath the tender and a transfer conveyor conveying the coal from the hopper to the locomotive;

Figures 9 and 10 are detailed sections taken on

lines 9—9 and 10—10 respectively of Figure 8;

Figure 11 shows partly in elevation and partly in section another modification of the connection between the tender hopper and transfer conveyor; and

Figures 12 and 13 are detailed sections taken respectively on lines 12—12 and 13—13 of Figure 11.

Referring to Figure 1, part of a locomotive 10 backhead 12 is shown and grate bars 11 inside the firebox are indicated. In the backhead is a hand-firing opening 13. Coal is conveyed from a hopper 1 located beneath the tender through a transfer conduit 20 up through a riser or elevating conduit generally indicated at 2 to distributing apparatus generally indicated at 3 located within the firing opening 13. Coal is moved through this conduit system by universally connected screw conveyors 1a, 20a and 39 respectively mounted in the hopper, in the transfer conduit and in the elevating conduit. The screw conveyor 1a may be driven by a gear located in the rear of the hopper, not shown, and in turn conveyor 1a drives the other two conveyors. 15 The delivery end of the riser conduit 2 is mounted on a frame structure generally indicated at 4 (Figures 1, 2 and 8) rigidly bolted to the backhead and encompassing the firing opening. The frame structure comprises a lower portion 14 extending generally along and downwardly from the lower edge of the firing opening 13; and an upper portion 15 having side plates 15a extending upwardly along the side of the firing opening and having a top section 15b extending across the top thereof. The frame 4 also has a rear or cover portion 16 itself provided with a hand-firing opening 17 aligned with the firing opening 13. The opening 17 is normally covered by any of the usual fire door constructions, not shown. This frame structure made up of sections 14, 15 and 16 may be constructed as one piece or in sections as disclosed.

Referring to Figures 1, 2, 7a and 8, the lower section 14 at its lower end rigidly supports a short conduit section 18 of the riser conduit 2. The conduit section 18 has at its lower extremity a flange 18a and at its upper extremity an externally spherically shaped connecting piece 18b forming part of a pivotal connection to be described. The lower section of the riser conduit 2 comprises a conduit section 19 bolted to the flange 18a of section 18. The conduit section 19 is additionally supported by a foot extending forwardly therefrom and secured to a bracket 55 47 attached to the mud-ring of the locomotive.

The conduit section 19 is expanded at its lower end to connect universally with the transfer conduit 20. The expanded portion has an internal spherically shaped portion 19b and an external circumferential flange 19c to which may be se-

cured a similarly flanged portion 21a of a retaining ring 21, also spherically formed internally. Confined within the spherically formed recess thus formed by the junction of the ring 21 and the conduit 19 is an externally spherically shaped portion 22a of a short sleeve section 22 which telescopically and slidably receives the forward end of the transfer conduit 20. The sleeve section 22 is retained against rotational movement with respect to the conduit 19 by a cylindrically formed pin 22b extending downwardly from the spherical portion 22a and confined within an elongated recess 23 formed by aligned recesses in flanges 19c and 21a of the conduit 19 and retaining ring 21 respectively. The conduit connection just described provides for universal movement between the conduits 19 and 20 and for longitudinal movement between the conduit 20 and the ball 22a to take care of relative movement between the locomotive and tender.

The rearward end of conduit 20 is universally connected with the discharge from the hopper 1. This connection is of known construction and will not be described further herein.

The delivery end of the riser conduit 2 comprises a mouthpiece generally indicated at 24 pivotally supported on the spherically shaped portion 18b of the conduit section 18. The lower end 24a of the mouthpiece has an internally spherically shaped surface which receives the ball end 18b and is pivotally held in place by means of pintle bolts 25 threaded through the end 24a and engaging holes 18c in the end 18b. These pintle bolts are aligned and form an axis x-x which lies in the vertical medial plane of the locomotive and stoker that is, the vertical plane that includes the longitudinal centerline of the firebox. Referring to Figures 4, 5 and 6, the mouthpiece 24 is shown as diverging and enlarging in cross-section towards its upper end and its cross-sectional shape gradually changes from circular, to elliptical, to a generally rectangular cross-section at its end. The inside surface 24b of the bottom wall of the mouthpiece and the bottom outside surface 24c thereof are substantially flat and lie at an angle of approximately fifty-six degrees to the horizontal. The upper inside surface of the top wall of the mouthpiece, generally indicated in Figures 4, 5 and 6 as 24d, is depressed inwardly between the ends of the mouthpiece and centrally along the length of the mouthpiece, the depressed portion being bounded laterally by a pair of arched passageways diverging in the direction of the flow of the fuel, for purposes hereinafter pointed out. The forward end of the bottom wall slidably rests on a flat projection 14d centrally located with respect to and flush with the top edge 14e of the wall 14f of the section 14 of the frame 4. The bottom wall terminates in a slightly V-shaped edge 24e, as best shown in Figure 2, the vertex of which is symmetrically aligned with said vertical medial plane of said mouthpiece.

The V-shaped edge 24e is so proportioned that when the mouthpiece 24 is in either of the extreme lateral positions, one-half of the V-shaped edge will coincide and be flush with edge 14e.

The top wall 24d of the mouthpiece 24 is constructed so as to form a pair of inverted channels 24f of arcuate formation. The outer walls of these channels blend into the side walls of the mouthpiece 24, while the inner walls of the channels merge into the center depressed section.

Referring to Figures 2 and 3, the mouthpiece 24 is adjustable about the axis x-x which axis

is perpendicular to the wall 14f and to the bottom 24c so that the bottom wall remains in flat sliding contact with the projection 14d for all positions of adjustment of the mouthpiece 24. 5 The adjustment is made by means of manually adjustable screws 26 threaded through bearings 26a in the side plates 15a. The screws abut against surfaces 24f on the outside of the mouthpiece and can effectively lock the adjustment. 10 The purpose of this adjustment will be described hereinafter.

Referring to Figure 3, coal rising in the mouthpiece is prevented from falling down between the sides of the mouthpiece and the frame 4 15 by sealing members 15c located inside the side plates 15a and forming with the curved faces 24g of the mouthpiece a seal maintained for all adjustments of the mouthpiece.

Referring to Figure 1, the upper edge of the 20 top side of the mouthpiece has a flat face 24h that slides under a corresponding face of the cover 16.

Referring now to Figures 1, 2 and 3, between the wall 14f of the frame 14 and the wall 24e 25 of the mouthpiece there are provided two gates 35 respectively pivoted on trunnions 33 mounted in the wall 14f. Each gate adjacent its trunnion support is cut out and provided with a curved edge 35a concentric with its trunnion support 30 and with the adjacent edge of the flat projection 14d so that a seal is maintained between the gate and the projection 14d for all positions of adjustment of the gates. The top edge 35e of each gate is so proportioned that when 35 the gate is lowered, the edge becomes flush with the top edge 14e of the wall 14f. The gates are adjustable by handles 35d and are locked in position by means of taper pointed set screws 35c located in the side plates 15a and engaging 40 with teeth 35b on the outer edge of the gates. The set screws are manually retractable from the locking position to permit changing the position of the gates.

As the gates are raised, they serve to reduce, 45 and so control, the amount of coal delivered to the sides and to the back corners of the firebox as will be described.

Supported by the frame 14, 15 within the firing 50 opening 13 is the distributing apparatus generally indicated at 3. This apparatus comprises a blast chamber 27, such as described in my Patent No. 2,090,628, from which issue high and low pressure jets. The high pressure jets issue through fingers 27a, which fingers also form a 55 riddle to separate the fine from the coarse coal, the fine coal falling between the fingers into the low pressure jet issuing from a longitudinal slot 27b.

As shown in Figures 3 and 7, the blast chamber is held in place by two sets of opposing screws 27c and 27d threaded through the side walls 15a. The screws 27c are tapered at their ends and engage in holes provided on opposite sides of the blast chamber. The screws 27d which are formed at their ends with plain cylindrical portions, are adapted to be screwed through the side walls 15a and the heads of the screws brought tightly against their seats on the outside of the side walls 15a. This construction provides a pair of aligned pins, one extending inwardly from each side wall 15a and spaced apart a definite distance. Immediately below the recess holes in the sides of the blast chamber 27 are slots milled out to an inverted U-shape, the semi-

circular sides of which rest on the pins formed by the screws 27d.

The blast chamber is installed by positioning the U-shaped slots over the pins 27d, and locking it in position by tightening screws 27c, after aligning the upper set of holes with the pointed ends of the screws. As the screws 27c and 27d are a slightly lesser distance apart than the recesses and the U-shaped slots, the pivoted ends of screws 27c exert a downward pressure on the last chamber causing the semi-circular sides of the U-shaped slots to bear hard against the pins 27d, thus securing the blast chamber rigidly in position without any possibility of vibration.

Referring to Figure 7, the low pressure steam is supplied by a pipe 27e at the right side of the drawing and the high pressure steam is supplied through a pipe 27f at the left side of the drawing.

Located beneath the blast chamber is a distributor plate 30 similar to that described in my Patent No. 2,128,940. The distributor plate has a three point suspension, two points of which are provided by studs 30a extending forwardly from the inside of the wall 14f and engaging the underside of the plate. The other support is provided by lugs 30b also extending forwardly from the underside of the wall 14f and forming a yoke to receive a tongue extending rearwardly from the plate. The distributor is locked in position by means of a rod 30c passing through a hole in the wall 15a, shown at the right side in Figure 7, through aligned holes provided in the yoke 30b and through a hole 30d in the tongue extension of the distributor plate 30. The rod 30c is held in place by a hook 30e secured to the frame member 14. When the handle portion of the rod 30c is hanging in a vertical position it is prevented from being dislodged from its position by the hook portion of the member 30e. This mounting provides for easy removal and replacement of the distributor plate by simply withdrawing the rod 30c to unlock the distributor plate and the reinsertion of the rod 30c to lock in the replaced distributor plate.

The under surface of the distributor plate may be cooled by the draft drawn in through a longitudinal slot 14g provided in the flange 14h extending from the wall 14f and bolted to the boiler backhead.

Referring now to Figures 1 and 2, the axis of the screw conveyor 39 lies in the vertical medial plane of the locomotive and stoker, and the flight of the screw conveyor 39 in the riser conduit 2 not only is tapered at its delivery end but also, starting at the point indicated at 39a, has its leading face sloped forwardly from the periphery to the hub to form an obtuse angle with the screw axis. And in addition, the tip of the conveyor screw is provided with a secondary vane 39b. The tapering of and the sloping of the flight commence at a point adjacent the point at which the conduit 2 commences approximately to diverge and increase in cross-section. As the coal feeds up through the transfer conduit 20 and the riser conduit 22 and reaches the enlarging mouthpiece 24 and the tapering flight 39a, the coal spreads sidewardly, fills the mouthpiece and feeds therefrom across the entire mouth area. This spreading and feeding action completely filling the mouthpiece is facilitated by the tapering of the flight, by the sloping of the flight as above described, by the secondary vane, by the slope of the top side of the mouth-

piece and its laterally diverging channel ways, as well as by the amount that the mouthpiece tilts upwardly from the horizontal. With the construction shown, the coal feeds from the mouthpiece in successive waves or avalanches which pour coal onto the distributing apparatus. The waves are synchronized with the turning of the screw conveyor 39, and each wave starts at one side of the mouthpiece and moves thereacross to the opposite side travelling in one direction only.

Furthermore, the coal pouring from the mouthpiece is relatively loose, i. e., is not packed into a conglomerate mass because both the tapering of the end of the flight of the screw 39 and the presence of the secondary flight 39b acting within the enlarging mouthpiece serve to condition the coal coming from the riser conduit. The coal thus conditioned is in a loosened condition in contrast to the packed condition it may be in in the transfer conduit and in the lower part of the riser conduit. Further, the flight 39 terminates appreciably below the top of the mouthpiece so that coal is not fed from the mouthpiece directly from the screw, but rather by the pushing action of the oncoming coal.

Further, with the construction of the mouthpiece described, the amount of coal fed from the sides of the mouthpiece is greater than that fed over the central portion so that more coal is supplied to the sides of the firebox than to the central portion thereof as is desired for efficient firing. But the amount of coal delivered to the back corners of the firebox may be controlled by means of the gates 35, which gates, as they are raised more and more, increasingly reduce the amount of coal reaching the extreme sides of the blast chamber and the channels 30f of the distributor plate, which channels supply coal to the back corners.

The turning of the screw conveyor 39 normally tends to feed more coal to the right side of the firebox in the construction shown in Figure 1 than to the left side thereof. That is, a section to the right of the longitudinal centerline of the firebox tends to receive more coal than the corresponding section located to the left of the centerline. The reason for this is that a screw conveyor of the type described tends to concentrate the coal on the side of the conduit adjacent the rising periphery of the rotating screw conveyor. This tendency, however, in the present embodiment is successfully corrected by adjusting the mouthpiece to one side of the vertical medial plane of the locomotive stoker and firebox represented by the line y—y as shown in Figure 2 so that a balanced delivery to the distributing apparatus is obtained. This adjustment may be made by manipulating the screws 26 after the stoker has been installed on the locomotive and the adjustment once made may be left indefinitely or readjusted from time to time as circumstances may require.

In Figure 3 the mouthpiece is shown aligned with the vertical medial plane of the stoker indicated by line y—y in Fig. 2, and in Figure 2 the mouthpiece is shown adjusted as for operation on a locomotive, the axis of the mouthpiece being shifted about its pivotal axis x—x so as to lie to the left of the vertical medial plane y—y.

This improved conveyor system which is simple to operate provides a stoker that is capable of maintaining a balanced and uniform coal delivery to the firebox and is also capable of delivering a greater or less amount of coal to any

portion of the firebox at the will of the operator, a necessity which may frequently arise due to the draft or other conditions peculiar to each individual installation.

Referring now to Figure 8 in this modification, the transfer conduit 100 instead of being connected in end to end relationship with the tender hopper 101 receives coal from the hopper 101 through a delivery opening 102. The rearward end of the conduit 100 is carried by a saddle 103 slidably mounted in channels formed by angle irons 104 secured to the tender frame. The supporting connection between the conduit 100 and the saddle 103 provides for universal movement by means of externally spherically shaped flange portions 105 operating in similarly spherically shaped recesses 106 in the saddle 103. Extending upwardly from the rear of the conduit 100 is a hopper 107 that loosely receives the downwardly extending sealing ring 102a to provide for relative movement between the two parts. Compression springs 108 carried by the hopper 107 keeps the sealing ring 102a in sealing contact with the hopper 101 adjacent the edges of opening 102 so that coal does not escape from the conveying system during its passage from the chute 102 to the hopper 107.

In the hopper 101 is a screw conveyor 109 driven from its rear end by a gear drive, not shown. The source of power for driving the screw conveyor is an engine generally indicated at 110 on the locomotive, which engine through a reducing gear generally indicated at 111 turns a telescoping drive shaft 112 which in turn rotates a pinion shaft 113 mounted in bearings 114 carried by the rearward end of the conduit 100. The pinion shaft at its rearward end through a universal connection drives telescoping drive shaft 115 which drives the above mentioned gear drive in the rear of the hopper.

Pinion shaft 113 drives the rear end of the conveyor screw in the conduit 100 through a pinion gear 116 on the shaft and a gear 117 (Figure 8) meshing with gear 116. Gear 117 is connected to drive the rear end of the screw conveyor.

The hopper 101 is provided with the usual crushing mechanism, not shown, and which, of course, is located to the rear of the discharge mouth 102.

Referring to Figures 11, 12 and 13, another modification of the connection between the transfer conduit 200 and the hopper 201 is shown. Extending forwardly from the hopper 201 is a delivery chute 202 which curves and opens downwardly into the ball of the ball-and-socket joint that connects the conduit 200 and the chute 202. The conveyor 209 in the hopper is driven from its rearward end by a gear 210 which is driven by a pinion gear 211 driven from the drive shaft 212 rotating in bearings provided on the hopper. The shaft 212 is in turn rotated by a drive shaft 213 corresponding to the drive shaft 112 shown in Figure 8. Referring again to Figure 13, pinion gear 211 also drives gear 214 which, through a telescoping drive shaft 215, rotates the conveyor screw 216 in the transfer conduit 200.

I claim:

1. In a firebox having a back wall provided with a firing opening and fuel distributing apparatus associated with said firing opening, the combination of a conduit system arranged so as to effect delivery of fuel to the distributing apparatus, said conduit system including a conduit section adapted to direct the flow of fuel delivered therethrough to said distributing apparatus, a

rotatable screw conveyor in said conduit section, said conduit section being adjustable independently of said distributing apparatus and of said screw conveyor to adjust the direction of the flow of fuel to said distributing apparatus.

2. In a locomotive stoker for supplying solid fuel to a firebox through a firing opening in the back wall thereof, including fuel distributing apparatus associated with said opening, a conduit system for delivering fuel to said distributing apparatus comprising the combination of a conduit section from which fuel flows to said distributing apparatus and a conveyor screw rotatable within said conduit section and having its axis lying in the vertical plane including the longitudinal centerline of said firebox, said conduit section being adjustable with respect to the axis of the conveyor screw about an axis intersecting the axis of the conveyor screw whereby to regulate the delivery of fuel to said distributing apparatus on opposite sides of said vertical plane.

3. In a firebox having a backhead provided with a firing opening, and having fuel distributing apparatus associated with said opening, the combination of a conduit system adapted to deliver fuel to said distributing apparatus and including a section fixed with respect to the distributing apparatus and having a delivery end, an adjustable section adapted to deliver fuel to said distributing apparatus, and means for pivotally mounting said adjustable section on the delivery end of said fixed section so as to provide an unrestricted passageway between the adjustable and the fixed sections for all positions of adjustment of said adjustable section.

4. In a firebox having a back wall provided with a firing opening and having fuel distributing apparatus associated with said firing opening, the combination of a fuel delivery system adapted to be arranged to deliver fuel to said fuel distributing apparatus, said system including a section having a fuel-guiding surface parallel to the fuel flow and adapted to guide the flow of fuel to said distributing apparatus, a rotatable screw conveyor in said section, said section being adjustable independently of said distributing apparatus, and independently of said screw conveyor, and adjustable means between said screw conveyor and said distributing apparatus adapted to control the flow of fuel to the sides of said distributing apparatus.

5. In a firebox having a backhead provided with a firing opening and having fuel distributing apparatus associated with said opening, the combination of a conduit system adapted to deliver fuel to the distributing apparatus and comprising a fixed conduit section adapted to be secured to but terminate remotely from the backhead, a movable conduit section pivotally supported upon said fixed conduit section and bridging the space between the distributing apparatus and the terminus of said fixed conduit section, the pivotal axis of said movable conduit section being disposed in the vertical axial plane of said fixed conduit section and approximately at right angles to the axis of said movable conduit section, and a screw conveyor in said fixed conduit section extending into said movable conduit section for moving fuel through said sections to said distributing apparatus.

6. In a locomotive stoker having a conduit system for conveying fuel from the locomotive tender to a firing opening in the locomotive backhead, and having distributing apparatus asso-

ciated with said opening, the combination of a frame adapted to embrace said firing opening and be attached to the backhead, a cover for said frame, and means on said frame for supporting said distributing apparatus, a riser conduit forming part of said system, and means extending from said frame for rigidly supporting the forward end of said riser conduit, a mouthpiece pivotally connected to said riser conduit and pivotable about an axis in the vertical axial plane of said stoker and perpendicular to the axis of said mouthpiece.

7. In a stoker for coal firing a locomotive firebox, and having a conduit system for conveying coal from the locomotive tender to distributing apparatus associated with a firing opening in the backhead of the locomotive firebox, the combination of a frame adapted to embrace said firing opening and be attached to the backhead, a cover for said frame having a hand-firing opening aligned with the said backhead firing opening, means on said frame for supporting said distributing apparatus, a riser conduit, means extending from said frame for rigidly supporting the forward end of said riser conduit, a mouthpiece pivotally connected to said riser conduit and pivotable about an axis in the vertical axial plane of said stoker and at right angles to the axis of said mouthpiece, and said mouthpiece having diverging side walls extending to and terminating at said distributing apparatus.

8. In a locomotive stoker for supplying coal to a firebox having a back wall having a firing opening therein, the combination of a housing adapted to be secured to the back wall and to enclose said firing opening, said housing having a pair of oppositely disposed rearwardly extending walls, a fuel delivery system adapted to deliver fuel to said opening including a conduit section mounted between said walls and tiltable laterally to adjust said section with respect to the walls, and adjusting and locking means carried by said rearwardly extending walls and engaging said section for moving it to adjusted position and locking it therein.

9. In a stoker for coal firing a locomotive firebox, and having a conduit system for conveying coal from the locomotive tender to distributing apparatus associated with a firing opening in the backhead, the combination of a housing adapted to encompass said firing opening and be supported on the backhead, a coal delivery mouthpiece adapted to terminate adjacent said distributing apparatus for delivering coal thereto, said mouthpiece having an upwardly sloping bottom coal supporting wall, and upwardly diverging side walls, a screw conveyor for moving coal through and conditioning it in said mouthpiece, and means for adjusting said mouthpiece to shift laterally its axis at an angle with respect to the axis of said screw conveyor to offset the tendency of the screw conveyor to concentrate the flow of coal from one side of said mouthpiece.

10. In a firebox having a backhead provided with a firing opening and having fuel distributing apparatus associated with said opening, the combination of mechanism adapted to effect delivery of fuel to the distributing apparatus and comprising a conduit system and conveying means enclosed therein, said conduit system comprising a conduit section adapted to be fixed to but terminate remotely from the backhead and a conduit section connected to said fixed section and bridging the space between the distributing apparatus and the terminus of said fixed section

and laterally adjustable with respect to the distributing apparatus, said conveying means comprising a rotatable conveyor having a spiral vane extending throughout said fixed section and into said adjustable section, the portion of said vane lying within said adjustable section having less fuel handling capacity than the portion in said fixed section so as to cause the mass of fuel to spread out laterally as it passes through said adjustable section.

11. In a stoker for coal firing a locomotive firebox, and having a conduit system for delivering coal from a tender to coal distributing apparatus associated with a firing opening in the firebox backhead, the combination of a coal delivery conduit having a bottom wall terminating in a coal delivering ledge over which coal flows to said distributing apparatus, said bottom wall sloping upwardly with respect to the horizontal, and oppositely disposed gate means between said delivering ledge and said distributing apparatus, said gate means being substantially parallel to said bottom wall and adjustable independently to increase effectively the lengths of the side portions of said bottom wall to control the amount of coal fed to the sides and rear corners of the firebox.

12. In a stoker for coal firing a locomotive firebox, and having a conduit system for conveying coal from the locomotive tender to the firing opening of the locomotive firebox, and distributing apparatus associated with said firing opening for distributing over the firebox coal delivered thereto, the combination of a riser conduit terminating in an expanding mouth portion, said mouth portion having a bottom coal supporting wall over which coal flows to said distributing apparatus and fixed side walls forming coal guiding surfaces, said bottom wall being at an angle with respect to the horizontal which angle is less than ninety degrees but greater than the effective angle of repose of the coal, and the fuel guiding side surfaces of said mouth portion diverging toward the delivery end and one of the side surfaces being inclined less from the vertical than the other, a rotatable screw conveyor in said riser conduit the delivery end of which stops appreciably short of the delivery end of said mouth portion, and the direction of rotation of the screw conveyor being such that a point on the periphery thereof adjacent the bottom wall moves toward the less inclined side surface as the screw conveyor rotates.

13. In a stoker for coal firing a locomotive firebox, and having a conduit system for conveying coal from the locomotive tender to the firing opening of the locomotive firebox, and distributing apparatus associated with said firing opening for distributing over the firebox coal delivered thereto, the combination of a riser conduit terminating in an expanding mouth portion, said mouth portion having an upwardly inclined bottom wall, and diverging side walls, one of the side walls being inclined less from the vertical than the other, a rotatable screw conveyor system in said riser conduit the delivery end of which stops appreciably short of the effective delivery edge of said bottom wall, the direction of rotation of the screw conveyor being such that a point on the periphery thereof adjacent the bottom wall moves toward the less inclined side wall as the screw conveyor rotates, and the delivery edge of said bottom wall being approximately V-shaped with the vertex thereof displaced from the vertical axial plane of the riser.

conduit, and the side of said V-shaped edge adjacent said less inclined side wall being generally higher than the opposite edge of said delivery edge.

14. In a stoker for coal firing a locomotive firebox, and having a conduit system for conveying coal from the locomotive tender to the firing opening of the locomotive firebox, and distributing apparatus associated with said firing opening for distributing over the firebox coal delivered thereto, the combination of a riser conduit terminating in an expanding mouth portion, said mouth portion having an upwardly inclined bottom wall, and diverging side walls, one of the side walls being inclined less from the vertical than the other, a rotatable screw conveyor system in said riser conduit the delivery end of which stops appreciably short of the effective delivery edge of said bottom wall, the direction of rotation of the screw conveyor being such that a point on the periphery thereof adjacent the bottom wall moves toward the less inclined side as the screw conveyor rotates, and the delivery edge of said bottom wall being approximately V-shaped with the vertex thereof displaced from the vertical axial plane of the riser conduit, and the side of said V-shaped edge adjacent said less inclined side wall being generally higher than the opposite edge of said delivery edge, and said mouth portion being adjustable to shift laterally the position of said V-shaped edge of said bottom wall and to change the angles of inclination of said side walls from the vertical to compensate for the tendency of the screw conveyor to concentrate coal delivery from one side of said mouth portion.

15. In a stoker for coal firing a locomotive firebox, and having a conduit system for conveying coal from the locomotive tender to the firing opening of the locomotive firebox, and distributing apparatus associated with said firing opening for distributing over the firebox coal delivered thereto, the combination of a riser conduit terminating in an expanding mouth portion, said mouth portion having a top wall, an upwardly inclined bottom wall and diverging side walls, one of the side walls being inclined less from the vertical than the other, a rotatable screw conveyor system in said riser conduit the delivery end of which extends into said mouth portion but stops appreciably short of the effective delivery edge of said bottom wall, the direction of rotation of the screw conveyor being such that a point on the periphery thereof adjacent the bottom wall moves toward the less inclined side wall as the screw conveyor rotates, and the top wall of said mouth portion being depressed lengthwise along part of its central portion to so direct the coal movement through the mouth portion that more coal flows from the side portions of the mouth portion than from the central portion thereof.

16. In a stoker for coal-firing a locomotive firebox, and having a conduit system for conveying coal from the locomotive tender to the firing opening of the firebox, and distributing apparatus forward of said firing opening for distributing over the firebox coal delivered thereto, the combination of a riser conduit terminating in an upwardly extending expanded mouth portion, a rotatable screw conveyor in said riser conduit for moving the coal therealong, successive cross-sections of said mouth portion from its receiving end to its delivery end having increasingly flattening oval contours, the respective long and short axes of which intersect along the median line of said mouth portion but at increasing distances from

the median line of the screw conveyor whereby the tendency for the rotation of the screw conveyor in the riser conduit to concentrate flow of coal therethrough to one side of the conduit is offset and the amounts of coal flowing from corresponding portions of said mouth portion are equal.

17. In a stoker for coal-firing a locomotive firebox, and having a conduit system for conveying coal from the locomotive tender to the firing opening of the firebox, and distributing apparatus associated with the firing opening for distributing over the firebox coal delivered thereto, the combination of a riser conduit terminating in an expanded mouth portion, a rotatable screw conveyor extending lengthwise of said riser conduit for moving the coal therethrough, and the coal-guiding surfaces and lower forward edge of said mouth portion being offset with respect to the axis of said screw conveyor whereby the tendency for the rotation of the screw conveyor in the riser conduit to concentrate flow of coal therethrough to one side of the conduit is offset and the amounts of coal flowing from corresponding portions of said mouth portion are equal.

18. In a stoker for coal firing a locomotive firebox, and having a conduit system for conveying coal from the locomotive tender to the locomotive firebox, the combination of a riser conduit terminating in an expanding mouth portion, said mouth portion having an upwardly inclined bottom wall and diverging side walls, one of the side walls being inclined less from the vertical than the other, a rotatable screw conveyor system in said riser conduit the delivery end of which extends into said mouth portion but stops appreciably short of the effective delivery edge of said bottom wall, the direction of rotation of the screw conveyor being such that a point on the periphery thereof adjacent the bottom wall moves toward the less inclined side wall as the screw conveyor rotates; and said stoker including a hopper substantially horizontally mounted beneath said tender, and a transfer conduit extending forwardly therefrom connecting with said riser conduit and inclined at least ten degrees from the horizontal, the lower section of said riser conduit being inclined at least forty degrees from the horizontal, and said bottom wall of said mouth portion being inclined at least fifty-six degrees from the horizontal.

19. In a stoker for coal firing a locomotive firebox, and having a conduit system for conveying coal from the locomotive tender to the firing opening of the locomotive firebox, and distributing apparatus associated with said firing opening for distributing over the firebox coal delivered thereto, the combination of a riser conduit terminating in an expanding mouth portion, said mouth portion having an upwardly inclined bottom wall and diverging side walls, one of the side walls being inclined less from the vertical than the other, gate means associated with said mouth portion to control the flow of coal to the distributing apparatus, and a rotatable screw conveyor system in said riser conduit the delivery end of which extends into said mouth portion but stops appreciably short of the effective delivery edge of said bottom wall, the direction of rotation of the screw conveyor being such that a point on the periphery thereof adjacent the bottom wall moves toward the less inclined side wall as the screw conveyor rotates.

20. In a firebox having a backhead provided

with a firing opening, and having fuel distributing apparatus associated with said opening, the combination of a conduit system adapted to deliver fuel to said distributing apparatus, said conduit system terminating at its delivery end in an upwardly extending mouth portion comprising side walls, a rear wall and a forward wall, said side walls diverging toward their delivery ends, and said rear wall being formed with a pair of arched passage-ways diverging from each other.

21. In a firebox having a backhead provided with a firing opening, and having fuel distributing apparatus associated with said opening, the combination of a conduit system adapted to deliver fuel to said distributing apparatus, said conduit system terminating at its delivery end in an upwardly extending mouth portion comprising side walls, a rear wall and a forward wall, said rear wall being formed with a pair of arched passage-ways diverging toward their delivery ends, and said forward wall changing from an arcuate transverse section to a substantially flat transverse section in the direction of the fuel flow.

22. In a firebox having a backhead provided with a firing opening, and having fuel distributing apparatus associated with said opening, the combination of a conduit system adapted to deliver fuel to said distributing apparatus, said conduit system terminating at its delivery end in an upwardly extending mouth portion comprising side walls, a forward wall and a rear wall, said rear wall having a portion converging toward said forward wall in the direction of the delivery end, and said converging portion being bounded laterally by a pair of arched passage-ways diverging in the direction of the fuel flow.

23. In a locomotive stoker, for delivering coal to the firebox of a locomotive, and having fuel distributing apparatus associated with said firebox, the combination of a conduit system adapted to deliver fuel to said distributing apparatus, said conduit system terminating at its delivery end in an upwardly extending mouthpiece, said mouthpiece having a receiving end and a delivery end, and coal guiding walls connecting said ends including a relatively flat upwardly extending bottom wall, upwardly extending side walls having concave cross sections and diverging from the receiving end to the delivery end, and an upwardly extending top wall depressed along a portion of its longitudinal centerline effective to form in conjunction with the side walls a pair of diverging channels, and a conveyor screw terminating adjacent the receiving end of said mouthpiece and delivering fuel directly thereto.

24. In a locomotive stoker for supplying coal to a firebox having a firing opening, the combination of a fuel supply conduit terminating in a fuel conditioning chamber having a delivery ledge extending across said firing opening and over which fuel flows to said firing opening, fuel distributing means forward of said delivery ledge for distributing the fuel over the said firebox, screw conveyor means in said supply conduit, a tapered worm provided in said conditioning chamber driven from the forward end of said screw conveyor and acting to thin and condition the fuel as it moves through said conditioning chamber and acting further to regulate the fuel flow over said delivery ledge, the bottom wall of said conditioning chamber sloping forwardly and upwardly at an angle appreciably greater than that of the corresponding wall of said supply con-

duit and reaching to said delivery ledge, a top wall converging forwardly toward said bottom wall and having a fuel guiding surface the central portion of which is depressed with respect to the side portions thereof, and means providing diverging side walls for said conditioning chamber adjustable with respect to the vertical for controlling the spreading movement of the coal in the conditioning chamber and for controlling the flow over the delivery ledge.

25. In a locomotive stoker for supplying fuel to a firebox through a firing opening in a back wall thereof, the combination comprising, a fuel supply conduit terminating in a fuel conditioning chamber having a delivery ledge extending across said firing opening and over which fuel flows to said firing opening, screw conveyor means in said supply conduit, fuel moving means in said conditioning chamber, the bottom wall of said conditioning chamber sloping forwardly and upwardly and at an angle appreciably greater than that of the corresponding wall of the supply conduit and reaching to the delivery ledge, a top wall converging forwardly toward said bottom wall and having a fuel guiding surface the central portion of which is depressed with respect to the side portions thereof, said depressed portion being adapted to cause the spreading of the coal in said conditioning chamber and to increase the concentration of the flow of the coal passing therethrough over the side portions of said delivery ledge, and means effectively providing diverging side walls for said conditioning chamber adjustable with respect to the vertical for controlling the spreading movement of the coal in the conditioning chamber and for controlling the flow over the delivery ledge.

26. A conduit section for use as a part of the fuel-delivery system of a locomotive stoker having a bottom wall terminating in a delivery ledge at the delivery end of said section, side walls diverging from the intake to the delivery end, and a top wall having an intermediate portion extending inwardly of the conduit section forming in conjunction with the side and bottom walls a pair of channels diverging from a zone in the rear of the delivery ledge toward the delivery end.

27. A conduit section for use as a part of the fuel-delivery system of a locomotive stoker having a bottom wall terminating in a delivery ledge at the delivery end of said section, side walls diverging from the intake to the delivery end, and a top wall sloping toward the bottom wall from the intake to the delivery end, an intermediate portion of said top wall extending inwardly of the conduit section forming in conjunction with the side and bottom walls a pair of channels diverging from a zone in the rear of the delivery ledge toward the delivery end.

28. A conduit section for use as a part of the fuel-delivery system of a locomotive stoker having a bottom wall, curved near the intake end and substantially flat at the delivery end of said section, said bottom wall terminating at the delivery end in a delivery ledge, side walls diverging from the intake to the delivery end, a top wall sloping toward the bottom wall from the intake to the delivery end, an intermediate portion of said top wall extending inwardly of the conduit section forming in conjunction with the side and bottom walls a pair of channels diverging from a zone in the rear of the delivery ledge toward the delivery end.
